UNITED STATES PATENT OFFICE.

JOHN SANDILANDS, OF SAN FRANCISCO, CALIFORNIA.

SCARF-RETAINER.

SPECIFICATION forming part of Letters Patent No. 293,093, dated February 5, 1884.

Application filed August 3, 1881. (No model.)

To all whom it may concern:

Be it known that I, JOHN SANDILANDS, a citizen of the Kingdom of Great Britain, residing in the city and county of San Francisco, State of California, have made and invented certain new and useful Improvements in Scarf-
Retainers; and I do hereby declare that the following is a full, clear, and exact description of my said invention, reference being had
to the accompanying drawings, in which—

Figure 1 is a view of a scarf with my device applied. Fig. 2 is a perspective view of my device detached.

My invention relates to scarf fastenings or devices for retaining gentlemen's scarfs and other neck-wear in position.

The object of my improvement is to produce a simple, effective, and inexpensive device for this purpose, which is readily applied to neck-wear of all styles and kinds, and when so applied does not add to the bulk or thickness of the material at the neck to any objectionable amount or degree.

The plate *a* is formed of thin sheet-brass, and is set upon an offset portion, *a'*. A button-hole slot, *b*, with an enlarged opening, *b'*, is formed in the portion *a*, to allow the passage

of the button or stud. Needle-holes *c* are provided around the offset portion *a'*, to facilitate attachment. To fix this plate, as well as to hold it in suitable position on the frame or stiff body of a made-up scarf, I form a tongue or extension, *a'*, upon the bottom end of the plate *a*, and in this extension I place the needle-holes *C C*. This lower part of the plate is then bent in at and across a line just below the button-hole *b*, so that the plate *a* sets out from the surface against which the lower part, *a'*, is placed. The amount of this bend or offset *d* is sufficient to give room for the head of the stud or button behind it.

Having thus fully described my invention, what I claim, and desire to secure by Letters Patent, is—

The herein-described fastening device for attachment to neck-wear, consisting of the plate *a*, provided with the button-hole slot *b b'*, and an offset portion, *a'*, for attachment to the scarf, as set forth.

JOHN SANDILANDS. [L. S.]
